UNITED STATES PATENT OFFICE.

CHARLES JOSEPH DRESEN, OF SPRING GREEN, WISCONSIN.

SHINGLER'S STRAIGHTEDGE.

1,414,556.

Specification of Letters Patent.

Patented May 2, 1922.

Application filed June 10, 1921. Serial No. 476,441.

To all whom it may concern:

Be it known that I, CHARLES J. DRESEN, a citizen of the United States, and a resident of Spring Green, in the county of Sauk and 5 State of Wisconsin, have invented a new and useful Improvement in Shinglers' Straightedges, of which the following is a full, clear, and exact description.

My invention relates generally to measuring devices and more particularly to measuring devices adapted for use in shingling operations, and it consists in the combinations, constructions and arrangements herein described and claimed.

15 In shingling a roof of a frame structure, the initial row or "course" of shingles is arranged along one lower edge of the roof parallel with the ridge-piece of the latter and that the shingles of the next row or 20 "course" overlie the upper portions of the shingles in the first course, as is well known. As is also well known, it is essential that the corresponding ends of the shingles of the second course and of each course thereafter 25 be alined with one another and that lines tangent to the ends thereof shall be parallel with the ridge-piece of the roof.

It is therefore an object of my invention to provide a device having means for detachably engaging shingles of a course to 30 maintain the device in position to indicate the positions of the shingles of the next row or course.

A further object of my invention is to 35 provide a device of the character described having a body portion formed with one edge thereof a true straight edge and having means for detachably securing the body portion in adjusted position on a roof, whereby 40 the shingles of a row or course will have their ends alined and be correctly positioned when arranged with their lower ends abutting the straight edge.

A further object of my invention is to 45 provide a device of the character described that has means for indicating the portion of each shingle of a course that is to be covered by a shingle of the next course in order that the several courses or rows of 50 shingles on a roof may be relatively arranged in accordance with a predetermined plan, such means being adjustable so that the extent of the portions to be covered may be varied as required.

55 A further object of my invention is to provide a device of the character described

that is relatively simple in construction and operation, easily applied and manipulated, and thoroughly practical commercially.

Other objects and advantages will appear 60 in the following specification, and the novel features of the invention will be particularly pointed out in the appended claims.

My invention is illustrated in the accompanying drawing, forming part of this 65 application, in which—

Figure 1 is a view, showing the device operatively applied,

Figure 2 is an enlarged plan view of the 70 device, and

Figure 3 is a section along the line 3—3 of Figure 2.

In carrying out my invention, I provide a body portion 1 which preferably is bar-like in form, as illustrated. The body portion 75 1 is made of any suitable material, such as wood, that is sufficiently light in weight to afford ease of handling and at the same time strong enough to be durable in service. The body portion 1 is fashioned to provide a true straight edge 2. Extending transversely 80 across the under face of the body portion 1 and at right angles to the straight edge 2 are parallel similar slots 3—3 arranged adjacent to opposite ends of the body portion. 85 Measuring bars 4—4 are respectively slidably disposed in the guide slots 3—3. Each is formed with a longitudinally extending slot 5 and a retaining bolt 6 has its shank projected through the slot 5 and through an 90 opening 7 through the body portion 1. A thumb nut 8 is screwed on the threaded end of the bolt 6 against a washer 9 that is disposed between it and the upper surface of the body portion so that each measuring bar 95 4 may be clamped to the body portion in adjusted position with respect to the latter when the thumb nut is tightened. The head of the retaining bolt will then be flush with the lower surface of the body portion, as 100 best seen in Fig. 3.

Each of the measuring bars 4—4 has marked on its upper face a scale indicated generally at 10 and having graduations representing linear measurements. The measuring bars 4—4 are each formed with an integral attaching member at its end remote from the straight edge 2, each attaching member consisting of a portion 11 extending at right angles to the under surface of 110 the bar 4 and an end portion 12 bent to extend in the same direction as the bar 4

and parallel therewith. The under surfaces of the end portion 12 and of the bar 4 are parallel with one another. The end portion 12 is tapering in that the upper surface 5 thereof is slightly inclined from its extremity to the point of its junction with the portion 11. The end portion 12 has its edges cut away at its extremity as indicated at 13 and 14. The inner side of the portion 10 11 is parallel with the straight edge 2 and the scale 10 on the upper face of the bar 4 is arranged to indicate the distance between the inner side of the portion 11 and the remote end of the bar 4. The upper 15 surface of the latter is likewise inclined from its extremity to a point intermediate its length, as best seen in Figure 3.

From the foregoing description of the various parts of the device, the operation 20 thereof may be readily understood. After the first row or course of shingles 15 have been secured to the sheathing 16 of a roof 17 along a lower edge of the latter with the upper ends of the shingles alined, the tapering portions 12 of the attaching members 25 are inserted at the lower ends of certain shingles between such shingles and the underlying sheathing until the inner sides of the portions 11 abut the lower ends of the 30 shingles. The thumb nuts 8 are then manipulated to permit adjustment of the body portion 1 with respect to the bars 4-4. The body portion is secured in adjusted position when the thumb nuts are tightened. 35 The straight edge 2 will then mark the line of the lower ends of the next row or course of shingles, portions of which will be superposed on the shingles of the first row or course. A glance at the scale 10 will reveal 40 the length of the portion of the shingles of the first course that will remain uncovered by the shingles of the second course since the straight edge 2 will be alined with the graduation indicating the measurement of 45 that portion. Since each of the bars 4-4 is provided with a scale 10, the body portion

1 can be readily arranged as required and the several courses of shingles may be spaced apart as desired.

It is obvious that a great saving in time 50 and labor will result when my device is employed. Each shingle will be correctly positioned when placed with its lower end abutting the straight edge 2 and consequently the care that has heretofore been necessary 55 need not be exercised in placing the shingles. The device can be instantly moved from one position to another since it is not secured to the roof by nails or like fastening means, as is usual in similar devices of which 60 I am aware.

I claim:

1. A device of the character described comprising a body portion formed with a transversely extending slot in its lower face, 65 a bar slidably disposed in the slot and having one end thereof arranged to extend beyond the adjacent edge of the body portion, said bar being provided with means at its other end for engaging a fixed support, and 70 means for clamping the body portion and the bar together.

2. A device of the character described comprising a body portion formed with one edge thereof a true straight edge and with 75 a plurality of spaced apart parallel slots extending transversely across one face of the body portion at right angles to the straight edge, a measuring bar slidably disposed in each slot and projecting laterally 80 of the body portion at opposite sides of the latter, each of said bars being provided with an attaching member at its end remote from the straight edge, said attaching member consisting of a portion integral with the bar 85 and extending at right angles thereto and a tapering end portion extending parallel with and in the same direction as the bar, and means for detachably securing the body portion to the bars.

CHARLES JOSEPH DRESEN.
